US00D715759S

(12) **United States Design Patent**
Choi et al.

(10) **Patent No.:** **US D715,759 S**
(45) **Date of Patent:** **** Oct. 21, 2014**

(54) **CELLULAR PHONE**

(71) Applicant: **LG Electronics Inc.**, Seoul (KR)

(72) Inventors: **Sanghyun Choi**, Seoul (KR); **Seungil Lee**, Seoul (KR)

(73) Assignee: **LG Electronics Inc.**, Seoul (KR)

(**) Term: **14 Years**

(21) Appl. No.: **29/450,642**

(22) Filed: **Mar. 20, 2013**

(30) **Foreign Application Priority Data**

Sep. 26, 2012 (KR) 30-2012-0046307

(51) **LOC (10) Cl.** **14-03**

(57) **CLAIM**

The ornamental design for a cellular phone, as shown and described.

DESCRIPTION

FIG. 1 is a front, right side, perspective view of a cellular phone showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front, left side, perspective view thereof in an open and in use state;

FIG. 9 is a front view thereof in an open and in use state;

FIG. 10 is a rear view thereof in an open and in use state;

FIG. 11 is a left side view thereof in an open and in use state;

FIG. 12 is a right side view thereof in an open and in use state;

FIG. 13 is a top view thereof in an open and in use state;

FIG. 14 is a bottom view thereof in an open and in use state; and,

FIG. 15 is a right side view thereof in a partially open state.

1 Claim, 13 Drawing Sheets
